R. M. ROBINSON

AUTOMATIC DERAILER WITH APPROACH LOCKING EQUIPMENT

Filed Dec. 22, 1923

UNITED STATES PATENT OFFICE.

ROBERT M. ROBINSON, OF LOUISVILLE, KENTUCKY, ASSIGNOR TO CHEATHAM ELECTRIC SWITCHING DEVICE CO., INC., OF LOUISVILLE, KENTUCKY, A CORPORATION OF KENTUCKY.

AUTOMATIC DERAILER WITH APPROACH LOCKING EQUIPMENT.

Application filed December 22, 1923. Serial No. 682,233.

The object of my invention is to provide automatic derailers which may be placed in trolley tracks adjacent to where the same cross railroads which derailers are interengaged with the signaling systems of the trolley road and railroad in such a manner that the signals on the railroad will have an additional feature in that they will function normally when the derailers are open and be set at stop for the protected zone when the derailers are set to allow a trolley car to pass and the trolley signals are normally set so as to correspond with the derailers, that is favorable when the derailers are closed and for dead stop when the derailers are open and this open condition is the normal one for the trolley track so that an approaching trolley car cannot pass the derailers unless all signals are favorable to such passage and no railroad train is approaching within the protected zone and after the trolley car has crossed the railroad track, the derailers are re-set so as to open and again restore the railroad track signals to normal. This object is accomplished by my invention, one embodiment of which is hereinafter more particularly set forth.

For a more detailed description of my invention, reference is to be had to the accompanying drawings, forming a part hereof, in which the figure is a diagrammatic view of a crossing of a steam railroad and a trolley road, together with the necessary electrical connections and appliances and the derailers.

The steam railroad track circuits.

The railroad track is made in the conventional manner and has signals of the conventional kind. This track is divided into blocks or sections insulated from each other, which, in the present case, are indicated 1T, 2T, 3T, and the signal system of this steam road is operated by power supplied from the usual feed wires BX and NX. In the present embodiment of my invention, it is assumed that an alternating current is employed for these feed wires, but it is obvious that a direct current may be employed in which instance storage batteries and resistances will be used instead of transformers and impedance coils. As this is obvi-

ous, further reference to this fact is unnecessary and for the purposes of a simple description, only an alternating system will be described. The feed wires BX and NX supply an alternating current to step down transformers 50 which are connected to the rails in the usual manner with an impedance coil 51 in a secondary circuit so that the transformers will not be injured when the rails are short circuited. From the foregoing, it is apparent that the two rails of each section are insulated from each other in the usual manner and these rails are short circuited whenever a train enters the block, as is usual in such systems.

The wire NX has a number of wires extending therefrom designated generically by the character 10 and one of these runs to a signal B at one end of the section 2T and another one runs to a second signal C at the other end of this section 2T while the wire BX has a corresponding number of wires designated generically by the character 8 which are connected, as will appear below.

One rail of the section 1T is connected by a wire 52 with the magnet T of a relay and the other lead 53 from this magnet runs to an armature 54 which makes connection with a wire 55 that runs to the other rail of the section 1T.

The section 2T has two wires 56, one to each rail, which wires run to a magnet 57 of a relay with two armatures or two circuit openers shifted by this magnet 57, one of these armatures or circuits being the one 54 above mentioned, and the other being 90 one 58 which will be referred to below.

The rails in the section 3T have two wires 59 and 60, the one 59 being connected to the armature 58 and the other 60 running to a magnet T' of a relay which has a second wire 61 running to the pivoted end of the armature 58.

The feed wire BX has one lead 8 that runs to a switch circuit controller 16 connected to the derailler switch 94 by a mechanical connection, not shown. The ground magnets N and R are parts of two stations one of which is designated generically by the character D which includes not only the derailler but the signals and connections on the trolley road and in the

drawings they are shown north of the steam railroad and south of the steam railroad there is a corresponding group of apparatus A which also has its magnets N and R. As will appear below, the magnets R are energized to close the derailers and the magnets N to open the same. The circuit controller 16 is connected with a corresponding circuit controller 16 in the apparatus A by means of a wire 62 and at the station A the circuit controller 16 is connected to a wire 32 that runs to a magnet of a stick relay 63 which also has a wire 10 connected therewith so that the circuit is closed through this magnet 63 only when the contacts are closed at 16, that is when the derailers at A and B are open. When these derailers are closed this circuit through this magnet is opened at the contacts 16, as above set forth. The wire 10 also has a branch just above the magnet 63 which runs to a magnet 64 which has another wire 9 which ends in a contact which is connected to an armature 65 under the interlocking relay TT' and this armature is connected by a cross wire 19 to a corresponding armature 66 which is connected to a wire 8.

The signal B, as above stated, has one wire 10 and in addition to this it has another wire 67 which runs to a contact over the armature 68 which armature is controlled by the magnet 63 and this armature 68 is connected by a wire 69 that runs to a contact over an armature 70 controlled by the magnet T' and this armature has a wire 71 that runs to a corresponding armature 72 under the magnet T which is adapted to drop on a contact connected to a wire 8 so that a circuit may be closed from the wire 10 to the wire 8 and through the wire 67, as just above set forth.

The signal C has one wire 10, as above stated, and it also has a second wire 73 which runs to a contact over an armature 74 which is controlled by the magnet 63 and this armature is connected to a wire 75 that runs to a point below an armature 76 controlled by the magnet T' and this armature is connected by a cross wire 77 with another armature 78 which connects with a contact above this armature and connected to a wire 8. This armature 78 is controlled by the magnet T so that through the wires 10 and 73 a circuit may be closed through the signal C.

The trolley road circuits.

Power is supplied to the trolley road not from the conductors BX and NX, but from a trolley wire 79 and its feed wires, which are omitted for the purposes of this case so as not to confuse the drawings, it being understood that as many feed wires are used as are required, as is usual in such cases. Assuming that power comes from the trolley wire it gets to the ground through connec-

tions with the trolley road or otherwise in the usual manner. The trolley wire connections are designated generically by the character 4 and the grounds by the character 2 which run to the trolley road 80 or to any other suitable ground connection, in the conventional manner. The trolley wire 79 is provided with two line contactors or trolley pans 81 and 82 each of which has at one side a continuous bar 83 connected to the trolley wire 79 by a connection 84 and each of these line contactors has two other bars which are insulated from each other and run parallel to their respective bars 83, and these bars form parts to two circuits 3A and 5A which circuits are insulated from each other. The circuit 3A has the outside parts of the line contactor at one side and the circuit 5A the corresponding inside parts. The circuit 3A runs at one end to an armature 85 under the magnet 64 where it may be raised under the influence of this magnet to close a contact in the wire 3B which is also connected to another wire by an armature 86 which in turn is connected to a wire 3C that runs to an armature 87 under a directional high voltage relay magnet F. Normally, this armature 87 is down and rests on the contact of a circuit 3D that runs to a second magnet E of this relay which has another lead running to the wire 12 and thence through a resistance 88 to the ground. When the armature 87 is raised under the influence of the magnet F it connects with a circuit 5B which has two branches, one running to the magnet F and the other to a contact under an armature 89 which is connected to the circuit 5A. Underneath these respective magnets E and F are two other armatures 90 and 91 with magnetic blow outs, the connections for which will now be described, it being understood that these respective armatures are raised or lowered by these respective magnets, the armature 90 being under the magnet E and the armature 91 under the magnet F. When either of these armatures is raised the other cannot be raised, the construction being the usual one for this purpose and when either is raised it connects with a line 13 which through a resistance 92 is connected to a wire 4 that runs to the trolley 79. The armature 90 is connected to a wire 14 which has branch wires 14 that run to a ground solenoid R and from thence to a ground 2. The armature 91 is similarly connected to a circuit 15 which has branch wires 15 that run to coils N which are grounded at 2, as above described. The common core to each set of solenoids N and R is connected not only to the switch 16, but also to a derailler, the derailler for the station A being designated 93 and the one for the station D being designated 94. When the solenoids R are energized, the derailers are closed so that a car can proceed on the trolley road and

then the switches 16 are open and when the solenoids N are energized the derailers are opened and the switches 16 are closed.

Signal connections for trolley road.

The signals for the trolley road have three colors, that is three hooded lights, red, white, and green. The circuits for these respective lights are designated RA, WA and GA for the A station and RD, WD and GD for the D station. In addition to these, there is a general power supplying wire designated 10 because it is connected to the wire NX. The circuits which will be described below are all 15 connected to this wire 10, but with one exception only one pair of lamps can be energized at a time under the circuits which will now be described.

Beginning with a wire GA which runs 20 from the bank of lamps 95 of the station A to the terminus which is the lower contact of an armature 96 under the magnet 63 and this armature 96 is connected through a wire 97 with a second armature 98 under the magnet 25 64 and when this armature 98 is raised it is in contact with a wire 99 that runs to 8 and an armature 100 which is also raised by the magnet 64 off of its contact. When the armature 100 is lowered it contacts with a wire 30 RA which will be described more fully below. This wire has a connection with an armature 101 under the magnet 63 which may be raised to close the circuit and this armature is connected to a wire 8. 35 The wire WA which runs from the bank 95 goes to a contact above the armature 96 and with which it is connected when the magnet 63 is properly energized. The third wire RA runs to the contact below the armature 100, as above described. The wire GD runs to the wire GA and the wire WD runs to the wire WA and the wire RD runs to the wire RA.

Operation.

In view of the foregoing, the operation of my automatic derailers with approach locking equipment will be readily understood if it be studied under the varying conditions 45 of its use. Assuming first that a train enters the protected zone going east before a trolley car going either north or south reaches the line contactors 81 or 82. As soon as the rails are connected in the section 1T they are 50 short circuited thereby cutting out resistance between the points 54 and 55 while the result that the magnet T is deenergized and drops its armatures 66, 78 and 72 to the position shown in dotted lines while the corresponding armatures 65, 76 and 70 of the magnet T' are held up and then a current may flow 55 through the armature 72 by way of the wire 8, wire 71, armature 70, wire 69, armature 68, wire 67 to signal B and wire 10 and thereby 60 changing the signal B so as to display a

safety signal which allows the train to proceed. Meanwhile, the derailers are in their open condition, which is the normal position, and this cannot be changed because circuits are opened through the armature 66 70 which opens a circuit through the magnet 64 and allows the armatures 85, 86 and 98 to drop so as to open circuits and the armature 100 to drop so as to close a circuit so that the red lights will continue to be shown at the 75 stations A and D.

When the train gets into section 2T of the steam railroad, it is in the zone of the crossing and then the rails of this section are short circuited thereby short circuiting the wires 56 80 and therefore the magnet 57 is deenergized and its armatures 54 and 58 will drop. As soon as they drop they open all circuits through both the magnets T and T' so that no circuit can be established through the 85 ground solenoids N and R and no circuits through any lamps, except the red lamps connected to the wires RA and RD, as above described, and the signal and derailing systems remain unchanged. When the train leaves 90 the section 2T and enters into the section 3T the magnet 57 is energized and raises the armatures 54 and 58 and the rails in this section 3T are short circuited thereby short circuiting the wires 59 and 60. This short circuiting of the wires 59 and 60 would cause the armatures 65, 76 and 70 to drop, were it not for the construction of the interlocking relay. This construction will now cause these armatures to be supported mechanically 100 by the interlock, so that they cannot drop until all sections of the track circuit have been cleared. As soon as the train leaves the section 3T the rails in this section are no longer short circuited and then the wires 59 105 and 60 are no longer short circuited with the result that a current will flow through the magnet T' and raise the armatures, above mentioned, break the circuit between 76 and 75 so that the signal C becomes red by 110 gravity.

If a train passes in the opposite direction, that is to the west along the steam road, the corresponding operations are had.

If a trolley car approaches the railroad track while the signals are all normal and the railroad track is clear, the first action of the trolley wheel is to bridge between the bar 83 of the line contactor and its corresponding bar 3A. This connection will take 115 place only for a small time and is the same no matter whether the trolley approaches from the north or south. The instant this circuit is closed, current can flow from the trolley wire through the wire 84, bar 83, trolley wheel and circuit 3A to armature 85, circuit 3B to armature 86 thence through circuit 3C to armature 87, thence through 120 3D to magnet E, thence through wire 12, resistance 88 and wire 2 to ground, thereby 125 130

energizing the magnet E and causing the same to raise the armature 89 and also the armature 90. The raising of the armature 89 will cause a circuit to be closed through the bars 5A so that when the trolley wheel leaves the bar of the circuit 3A and enters upon the bar of the circuit 5A the magnet E will remain energized and the armatures 89 and 90 will remain raised. As long as the armature 90 remains raised, the solenoid R will be energized through the circuits, above described, and the energizing of these magnets will open the circuit controllers at 16 and so prevent any current from flowing through the wire 32 and thereby deenergize the magnet 63 so that the various armatures 68, 74, 96 and 101 will drop and open the circuits connected therewith, as above described, and close the other circuits, that is a circuit will be closed through the armature 96 and wire GA which gives the motorman on the car the signal to proceed. When the trolley wheel passes out of the contactor 81, or the contactor 82 as the case may be, the circuits closed through this contactor are opened and remain open so that the motorman can proceed to cross the railroad track and meanwhile stop signals are displayed at B and C by gravity and prevented from being set to safe by the de-energization of relay 63. When the trolley wheel reaches the second contactor, say the contactor 82 on the assumption that it has left the contactor 81 and is going north, a circuit is established between the bar 83 and the circuit 5A and then current passes through the armature 89, circuit 5B, magnet F, wire 12, resistance 88 and ground 2, whereby the magnet F is energized and the two armatures 87 and 91 are raised. Through the armature 91, a circuit 15 is closed which energizes the ground magnets N and shifts the cores accordingly, so as to open the derailer and close the switches 16 and as soon as the trolley wheel gets off the section 5A and on to the section 3A a circuit is established through the armature 85, circuit 3B, armature 86, circuit 3C, armature 87, circuit 5B, magnet F, wire 12, resistance 88, ground 2 so that the armatures 91 and 87 will remain raised until the trolley wheel leaves the second contactor 82.

In the preferred embodiment of my invention, the armatures 90 and 91 have magnetic blow outs so that no distinctive arcing will occur in connection with these armatures when circuits are broken.

From the foregoing, it appears that the railroad will have the right of way if a train gets on the section 1T or section 3T before a trolley wheel reaches the line contactors 81 or 82 and if a trolley wheel reaches these contactors prior to the train reaching these sections, the trolley car will have the right of way. If a train should

reach one of these sections 1T or 3T at the same time, a trolley reaches a line contactor, the train will have the right of way because the relay T or the relay T' will be quicker in its action than the ground solenoids and so keep the derailers open. 70

In order that there may be no misunderstanding the term "prohibited zone" is here defined. The prohibited zone is the zone which may be occupied so as to prevent the signals for being clear on the track crossing the one where the prohibited zone obtains. In this application the prohibited zone is shown on the steam railroad so that if a steam train is within the zone the derailers 80 on the trolley road will be set so as to prevent the approach of any trolley car to the steam railroad. If no train be within this prohibited zone, it will be possible to get by these derailers provided that the instructions given by the signals are followed. 85

It will be understood that the trolley signals function in the normal manner, that is when the derailers are open the red signals RA and RD show and also the white 90 signals WA and WD which means proceed with caution. If a train be on the railroad within the prohibited zone the white signals will not show at all because the armature 98 will fall. Assuming that the "proceed 95 with caution" signal appears, the car passes under a line contactor, say the line contactor 81, and thereby causes these two signals to be extinguished and the green or "proceed" signal to be displayed. When 100 the trolley wheel passes under the other contactor, say the contactor 82, the green light is extinguished and the original red and white signals again appear.

While I have shown and described one 105 embodiment of my invention, it is obvious that it is not restricted thereto, but that it is broad enough to cover all structures that come within the scope of the annexed claims. 110

Having thus described my invention, what I claim is:

1. In combination, a railroad track having three successive insulated sections, a trolley track intersecting the central section, a track circuit for each of said sections comprising a source of current and a relay adapted to be short circuited by the passage of a train, the track relays of the end sections having their armatures interlocked, the track relay for the central section controlling said interlocking relays, derails in said trolley track, signals for said railroad track and trolley track and means controlled by said relays and said derails for giving signals and operating said derails. 115 120 125

2. In combination, a railroad track having three successive insulated sections, a trolley track intersecting the central section, a track circuit for each of said sections com- 130

- prising a source of current and a relay adapted to be short circuited by the passage of a train, the track relays of the end sections having their armatures interlocked, 5 the track relay for the central section controlling said interlocking relays, derails in said trolley track, signals for said railroad track and trolley track, means controlled by the relays in the end sections and said derails for operating said signals and maintaining said derails open and means controlled by the relay in said central section 10 for maintaining said signals and derails in status quo.
- 15 3. In combination, a railroad track having three successive insulated sections, a trolley track intersecting the central section, a track circuit for each of said sections comprising a source of current and a relay adapted to be short circuited by the passage 20 of a train, the track relays of the end sections having their armatures interlocked, the track relay for the central section controlling said interlocking relays, derails in 25 said trolley track, signals for said railroad track and trolley track and means controlled by the relays in the end sections and said derails for operating said signals and maintaining said derails open.
- 30 4. In combination, a railroad track having insulated sections, a track circuit for each of said sections comprising a source of current and a relay adapted to be short circuited by the passage of a train, a trolley 35 track intersecting one of said sections, a trolley wire therefore, contacts carried by said wire upon opposite sides of said railroad track, derails in said trolley track, circuits including said contacts for operating said derails and means controlled by said railroad track relays controlling the operation 40 of said derails.
- 45 5. In combination, a railroad track having three successive insulated sections, a trolley track intersecting the central section, a track circuit for each of said sections comprising a source of current and a relay adapted to be short circuited by the passage 50 of a train, the track relays of the end sections having their armatures interlocked, the track relay for the central section controlling said interlocking relays, derails in 55 said trolley track, signals for said railroad track and trolley track and means whereby the signals upon said railroad track are controlled by the position of said track relays and derails.
- 60 6. In combination, a railroad track having three successive insulated sections, a trolley track intersecting the central section, a track circuit for each of said sections comprising a source of current and a relay adapted to be short circuited by the passage 65 of a train, derails in said trolley track, signals for said railroad track and means gov-
- erned by the position of said derails and by said relays controlling said signals.
7. In combination, a railroad track having three successive insulated sections, a trolley track and a trolley wire intersecting the central section, contactors on said trolley wire, a track circuit for each of said sections comprising a source of current and a relay adapted to be short circuited by the passage of a train, a stop and proceed signal in each end section and means controlled by said track relays upon the entry of a train into one end section and said contactors to give the proceed signal at said section and to maintain said signal in this condition until the train enters the other end section.
8. In combination, a railroad track having three successive insulated sections, a trolley track and a trolley wire intersecting the central section, contactors on said trolley wire, a track circuit for each of said sections comprising a source of current and a relay adapted to be short circuited by the passage of a train, a stop and proceed signal in each end section and means controlled by said track relays upon the entry of a train into one end section and said contactors to give the proceed signal at said section and to maintain said signal in this condition until the train enters the other end section and means for maintaining the stop signal in said other end section until entry of the train therein.
9. In combination, a railroad track having three successive insulated sections, a trolley track intersecting the central section, a track circuit for each of said sections comprising a source of current and a relay adapted to be short circuited by the passage of a train, a trolley wire for said trolley track, contactors upon said trolley wire on each side of said railroad track, stop and proceed signals upon said railroad track and means controlled by said contactors and relays for holding the stop signals upon said railroad track when a trolley passes a contactor prior to the entrance of a train on an end section.
10. In combination, a railroad track having insulated sections, a trolley track intersecting one of said sections, a track circuit for each of said sections comprising a source of current and a relay adapted to be short circuited by the passage of a train, said relays controlling signals for said track sections, derails in said trolley track, signals for said railroad track, a switch connected to each derail so as to be closed when the derail is open and vice versa and means controlled by said switches also controlling the signals for said railroad track.
11. In combination, a railroad track having insulated sections, a trolley track intersecting one of said sections, a track circuit

for each of said sections comprising a source of current and a relay adapted to be short circuited by the passage of a train, said relays controlling signals for said track sections, derails in said trolley track, a trolley wire, contactors carried by said wire, means controlled by said contactors for operating

said derails and said signals and a stick circuit also controlled by said contactors for holding said derails in position.

10

In testimony whereof, I have hereunto set my hand and seal this 6th day of November, 1923.

ROBERT M. ROBINSON.
